EXCAVATOR

Hans Lundstrom, St. Louis, Mo., assignor of two-thirds to Ida Lundstrom, and one-third to Joseph Magidson and Phelix B. Magidson, all of St. Louis, Mo.

Application June 15, 1936, Serial No. 85,284

10 Claims. (Cl. 214—138)

This invention relates broadly to excavators, of the type used by road builders, building contractors, and many others, and well known, and has among its objects the production of such excavators that will be especially adaptable to and capable of a maximum number of uses, which is easily constructed and operated, speedy and simple in operation and construction, economical, and otherwise satisfactory and efficient for use wherever deemed applicable.

The invention has among its objects, to produce an excavator having a dipper and a carrying boom therefor, the boom being telescopic in construction and action, and the dipper being operably connected to both the fixed and movable parts of said telescopic boom, in such a way that said dipper will have a maximum digging radius, enable better and easier dumping, and permit of very close jack-knifing of the dipper against said boom.

The invention has another object, to provide a dipper so mounted to said telescopic boom that when the excavator is not in use, it will provide greater stability and minimize any overturning tendency of the excavator, while at the same time permitting the mechanism to be of minimum height to permit of digging in places of low overhead clearance and to more easily transport the entire mechanism.

A further object of my invention is to provide means for easily and readily mounting and remounting the dipper from the boom, to permit the dipper to be reversed so as to dig in either forward or backward direction, as required, and thereby provide for maximum use of said device.

An added object of the invention is to provide a novel latch for the dipper, whereby the latter may be securely held in latched position against accidental dumping and yet may be readily, easily and conveniently dumped when required.

A still further object of the invention is to provide means automatically operated during the usual dumping and closing of the dipper, to clean and scrape the interior of the latter, thereby obviating the necessity of frequent manual cleaning, and hence increasing the effective carrying load of each digging stroke of the dipper.

Another added object of my invention is to provide a novel hoisting and digging connection between the dipper, boom and machine, that the operation will be sturdy, even and effective.

Many other objects and advantages of the construction herein shown and described will be obvious to those skilled in the art to which this in-

vention appertains, from the disclosures herein given.

To this end, my invention consists in the novel construction, arrangement and combination of parts herein shown and described, and uses mentioned, as will be more clearly pointed out in the claims hereunto appended.

In the drawings, wherein like reference characters indicate like or corresponding parts throughout the drawings,

Figure 1 is a side elevation of my improved excavator, as used for forward digging;

Figure 2 is a similar view of the same, but showing the dipper reversed, as used for back digging;

Figure 3 is a top plan view of the mechanism shown in Fig. 1;

Figure 4 is a longitudinal cross-sectional detail of the dipper;

Figure 5 is a transverse cross-sectional detail of the boom parts, taken substantially on the line 5—5 of Fig. 3; and

Figure 6 is a top plan view of the device shown in Fig. 2.

Referring more particularly to the drawings, wherein I have illustrated a preferred embodiment of my invention, only a fragment of the cab, machinery deck or machine A is indicated, the same being of any desired or suitable construction, and generally portable, as by means of the endless conveyor 1, so that it may be moved from place to place as required. The deck is also generally completely rotatable so that a maximum of digging range may be had from each setting of the machine. 2 indicates the gantry or other forward part of the deck, and to which the pulleys, sheaves, or other operating line carriers may be mounted.

Instead of having a boom of fixed length on the forward end of the machine, and to which is fixed a vertically movable dipper stick carrying a bucket, dipper or other digging element at its lower end, I have provided an entirely novel and functionally different structure, as will now be described.

The boom member that I employ is of telescopic construction, composed of a pair of longitudinally extensible and contractile elements relatively of one another, the relatively stationary element 3 being pivoted or otherwise hinged at one end to the forward end of said machine, so as to be movable in an up and down direction, and having its other end preferably upwardly projected as at 4. This element 3 is adapted to slidably receive the relatively movable boom element 5, and may be of channel-shape in transverse cross-section, as shown in Fig. 5, to provide said guideways.

The relatively movable boom element 5 has its forward end projected forwardly and downwardly as at 6, said end being forwardly beyond the adjacent end of the stationary boom element at all 5 times.

The digging element, such as the dipper B, is carried at the forward ends of said boom elements, and is detachably reversible so that it may be used for digging either forwardly or backwardly, relatively of said machine, Fig. 2 illustrating use as a back-digger, while the other views show its use as a forward digger.

This dipper may be of any suitable size and shape, as for example, composed of a pair of opposed side walls 7-7 extending substantially vertically, a rear wall or back 8, and an end wall 9, the rear and end walls cooperating in a movable manner, as will be more clearly herein-after set forth. Teeth 30 may be fixed to the 20 dipper at its open side, if desired.

Said dipper is movably connected to both of the boom elements, there being a pivot pin 10 between the opposed sides 7-7 of the dipper, for pivotal engagement through the forward ends 25 of a pair of links 11-11, each of said links being pivoted at its rear end to said upwardly extending projection 4-4 of the stationary boom element, the axis of said pin 10 being substantially in the transverse median plane through said dipper.

30 A pair of pin-receiving apertures 12 and 13 are provided through the side walls of said dipper to either side of and substantially like distances below the apertures for receiving said pin 10, the apertures 12 and 13 being closely adjacent the 35 bounding edges of the front and rear of said dipper, so that either the set of apertures 12 or 13 may be used selectively, for mounting the dipper for forward or backward digging, as desired.

Assuming that it is desired to mount the dipper 40 for forward digging, as shown in all the drawings, but Fig. 2, then said dipper is pivoted at 10 to the forward end of said links 11-11, and a pin 14 pivotally interconnects the downturned projections of the movable boom with said dipper 45 through the pin openings 12. Obviously, in order that the dipper may be conveniently, easily and practically reversed from time to time, for either backward or forward digging, said pins are preferably removably or detachably inserted into 50 place.

For operating the movable part of the boom in its necessary direction to enable the dipper to fill in digging, I provide a control line L, one end of which is dead-ended at 15 to an 55 axle 16 removably connected to the upper ends of the side walls of the dipper and carrying a pair of sheaves 17-17, said line then being threaded through said sheaves and gantry and around a loose pulley 18 adjacent the rear end of 60 said movable boom element, the other end of said line leading into the machine, so that operation of this last-mentioned line end at the machine will actuate the movable boom element forwardly, while at the same time actuating the 65 dipper in its digging, it being especially noted that when the dipper is at its rearmost position, as shown in dotted lines in Fig. 1, said links are substantially parallel with the down-turned and forwardly projecting ends 6-6 of the fixed 70 boom element, thus permitting the dipper to be brought up very close under the boom, or closely jack-knife, so that it is possible to commence the digging cut from substantially that point as its rearmost point, and continue said cut forward- 75 ly for a considerable distance, hence increasing

the digging radius of the excavations over and beyond that normally obtainable in digging operations.

When it is desired to retrieve the dipper, after dumping in a manner to be hereinafter described, a pull line P having its rear end leading into the machine and its forward end connected to any suitable part of the dipper so as to bring the latter up close against the under side of the boom to start the dig, is pulled, as required, this retrieving of the dipper also acting to re-latch the dipper as will be more clearly hereinafter set forth.

The dipper preferably has its end and rear walls movable relatively of one another and of 15 the fixed side walls 7-7, so as to open the dipper for dumping and re-closing it thereafter, the control means for said movable walls not only causing said opening and closing movements, but in addition making the dipper self-cleaning. 20 This self-cleaning feature is especially important, not only in making for easier and more efficient operation of the dipper itself, but by increasing the effective load-carrying capacity of the dipper. The dipper is cleaned at each dumping 25 operation, thereby obviating the necessity of manual cleaning of the same.

The end wall 9 is pivoted at its forward edge to said pair of side walls 7-7, and the rear wall is provided with a pair of inturned flanges 30 38, 38 of a height increasing from a point adjacent its lower end to one adjacent its upper end, said flanges being closely adjacent and substantially parallel to the inside surfaces of said side walls. Said rear wall is pivoted intermediate 35 its top and bottom to said pair of side walls, as at 19, and a pair of link plates 20-20 operably link said end and rear walls together, each of said link plates being interposed between said side walls and inturned flanges, and being pivotally connected at one end to one of said flanges, as at 39 and at its other end to said end wall of the dipper, as at 40. Consequently, the opening and closing of the dipper will cause the link plates to substantially scrape the side walls, and 45 cause the inturned flanges to substantially scrape said links.

The latch means has a finger 21 pivoted to the lower end of the rear of the dipper and movable up against the under side of the rear edge of 50 said end wall of the dipper, to hold said end and rear walls in closed position when said finger is thus retained in place. A bell-crank 22 is pivotally connected to the upper end of said movable rear wall 8, a link 23 interconnecting said bell-crank with 55 said finger 21 to actuate the two in unison, a spring 24 normally pressing said link in the direction to release or unlatch said finger.

An offset 25 is fixed to the upper end of the rear wall of the dipper and recessed to receive 60 said movable bell crank 22, said offset 25 bearing against a stop 26 carried by a stationary part of the dipper, near the top of the latter, said stop being spring-pressed to normally abut the said offset when the dipper is closed, but being 65 liftable to permit said offset to pass said stop when desired. Cam means 27 is also carried by said part of the dipper and controlled by a trip line 28 leading to the machine, so that actuation of said trip means through the line 28 moves said 70 cam to lift said stop and permit the load in the dipper to move the rear and end walls to open position, the offset and bell crank passing said stop to permit this action.

After dumping, a pull on the line P will first 75

actuate the open walls to closed position and reset the latch, and continued pull will retrieve the dipper to next digging position. In order to accomplish this result, the forward end of the line **P** may be loosely threaded through an eye **41** secured to the movable wall **8** a short distance above the pivotal axis **18**, before being secured to said pivotal axis. Hence, after the dipper has been tripped, and the rear wall is in the position shown in dotted lines in Fig. 4, a pull on the rope **P** will pull the rear wall at the eye-bolt, tending to turn the rear wall about said pivotal axis **18**, and closing the dipper.

Thus, it is seen that by actuating the control line **L** will telescopically extend the overall length of the boom, while at the same time pivoting the dipper about both of its pivotal connections to the boom elements, until the end of the cutting or digging stroke, whereupon the dipper may then be directed in proper position for dumping its load, said dumping being rapidly accomplished by a pull on the trip line **28** to release the dipper latch, whereupon the load itself will spread the movable walls of the dipper to permit such discharge of load. The retrieving line **P** is now pulled, the initial pull re-latching the dipper, and further pull swinging the dipper back to its original position for the next dig forwardly.

For many digging operations it is desirable that the dipper be actuated toward the machine or backwardly to fill, and in my device it is quite easy to change the dipper so that it may dig either forwardly or backwardly, this change being effected simply through the removal of several pivotal connections holding the dipper in place, and then replacing said pivotal connections in a manner now to be explained further.

To assemble the dipper for back-digging, after its use as a forward digger, the three pivotal connections **10**, **14**, and **16** are temporarily removed, and the dipper then turned so that its teeth extend in the reverse direction, namely rearwardly, after which the pivotal connections **10** and **16** are replaced into their positions from which they were removed, and the other pin, **14**, is placed through the now adjacent pair of apertures **13**. In this position of the dipper, the line **28** may be slightly rearranged so as to continue to be controlled from the machine as heretofore, as for example, by extending forwardly and thence down over the pin **10** for connection to the cam control of the latch, somewhat as shown in Fig. 2.

The pull line **P** now leads to the open side of the dipper and is free of the latch means. In this back-digging position of the dipper, the latch trip or release is through the line **28** as previously mentioned, but the resetting of the latch may be automatically accomplished, as by the threading of a line **T** about a loose pulley **29** mounted on the forward end of the stationary boom element, one end of said line being dead-ended adjacent to and on the forward end of the movable boom element, and the other end being dead-ended to the upper portion of the rear wall of the dipper. Hence, after the dipper has been dumped, and the dipper and movable boom element are actuated back to their initial digging position (and which in this instance is of course farthermost from the machine), the line **T** will become taut, its length being such that it will just accommodate the opening of said dipper, and bring said movable walls to their closed position for the next dig.

Even in this position of the dipper for back-ward digging, there is an unusually large digging radius, on account of the fact that the dipper may

be brought up very close under the boom, said dipper being connected directly to the boom and not through the usual intermediary of a dipper stick.

Having thus described my invention, it is obvious immaterial modifications may be made in the same without departing from the spirit of my invention; hence I do not wish to be understood as limiting myself to the exact form, arrangement, construction and combination of parts herein shown and described, or the uses claimed, except as limited by the state of the art to which this invention appertains and the claims hereunto appended.

What I claim as new and desire to secure by Letters Patent is:

1. In an excavating machine, a pair of relatively movable boom members, a reversible dipper, a link having one end pivoted to the end of one of said boom members and the other end pivoted detachably to said dipper, and means for pivotally connecting the adjacent end of the other boom member selectively to said dipper at a pair of spaced points beneath the pivoting point of the dipper and link, whereby said dipper may be reversed to dig either forwardly or backwardly.

2. In an excavating machine, a pair of relatively movable boom members, a dipper, a link having one end pivoted to the end of said movable boom member, detachable means for pivotally connecting said dipper to the other end of said link, means for selectively pivotally connecting the adjacent end of the other boom member to said dipper at either of a pair of spaced points beneath said pivotal point of the dipper and link, whereby said dipper may be reversed to dig either forwardly or backwardly, and operating means interconnecting said movable boom member and dipper to actuate them in unison from said machine.

3. In an excavating machine, a pair of relatively movable boom members, a dipper, a link pivoted at one end to the end of one of said boom members and at the other end to said dipper, and means for detachably pivotally interconnecting the end of the other of said boom members to said dipper selectively at either of a pair of spaced points beneath and substantially equidistant from the pivotal point of said link and dipper and to either side of said point, whereby said dipper may be used for digging either forwardly or backwardly relatively of said machine.

4. In an excavating machine, a boom pivoted for up and down movement, a dipper connected to said boom and having an end wall and a rear wall movably interconnected to open and close in unison, a latch maintaining said end and rear walls closed, a latch stop carried by a fixed part of said dipper, and a cam operable from said machine to move said stop from its normal locking position with said latch to permit releasing movement of said latch.

5. In an excavating machine dipper, an end wall and a rear wall movable in unison to open or close, and link plates interconnecting said walls and moving in a plane substantially parallel to said side walls to wipe excess material from said side walls of the dipper upon movement of said movable walls.

6. In an excavating dipper, fixed side walls, an end wall and a rear wall pivoted to said side walls to move in unison to open or closed position, link plates pivotally interconnecting said rear and end walls and moving in a plane substantially adjacent and parallel to said side walls to scrape

excess material from said side walls of the dipper upon movement of said end and rear walls relatively of said side walls.

7. In excavating machines, a dipper having fixed side walls and a movable end wall and rear wall, inturned flanges on said rear wall in a plane substantially parallel to said side walls, and link plates at either side of said dipper, interconnecting said end and rear walls and movable in a plane between said flanges and side wall so that said link plates and flanges wipe adjacent surfaces during opening and closing movement of the dipper.

8. In an excavating machine dipper, fixed side walls, an end wall and a rear wall movable relatively thereto to open or close said dipper, and means for interconnecting said movable walls so that said movement cleans them of excess material and comprising flanges carried by said rear wall in a plane adjacent and parallel to the side walls and extending from substantially the bot-

tom of the inside of said dipper to adjacent the inside of the top of the same, and link plates at either side of said dipper between said flanges and side wall and interconnecting said end wall and rear wall so that said links wipe said side walls and said flanges wipe said link plates during opening and closing movements of said dipper.

9. In an excavating machine, a boom, a dipper, and means for pivotally connecting said boom to either of a pair of spaced pivotal points selectively on said dipper, whereby the latter may be removably reversed to dig either forwardly or backwardly relatively of said boom.

10. In an excavating machine, a boom, a bucket having a plurality of pivotal points spaced transversely intermediate its front and rear, and means for pivotally removably connecting said boom to said bucket at one of said points for forward digging and to the other of said points for reverse digging.

HANS LUNDSTROM.

20
